United States Patent Office

Des. 184,422
Patented Feb. 17, 1959

184,422

SAUCE PAN

Richard B. Cronheim, St. Louis, Mo.

Application March 5, 1958, Serial No. 49,916

Term of patent 14 years

(Cl. D44—1)

FIG. I

Des. 184,422

PAGE 2

FIG. 2

FIG. 3

FIG. 4

FIG. 5

FIG. 6

Fig. 1 is a perspective view of a sauce pan embodying my new design;

Fig. 2 is a side elevational view thereof;

Fig. 3 is a top plan view thereof;

Fig. 4 is an exploded perspective view showing the lid in removed position;

Fig. 5 is a longitudinal sectional view thereof; and

Fig. 6 is a rear end elevational view thereof.

I claim:

The ornamental design for a sauce pan, substantially as shown.
